UNITED STATES PATENT OFFICE.

LOUIS F. BONALY, OF KICKAPOO TOWNSHIP, LEAVENWORTH COUNTY, KANSAS,
ASSIGNOR OF ONE-HALF TO FREDERICK M. PLANCK, OF KANSAS CITY, MISSOURI.

DOOR-LOCK.

1,164,982.

Specification of Letters Patent. Patented Dec. 21, 1915.

Application filed November 20, 1913. Serial No. 832,078.

To all whom it may concern:

Be it known that I, LOUIS F. BONALY, a citizen of the United States, residing in Kickapoo township, in the county of Leavenworth and State of Kansas, have invented certain new and useful Improvements in Door-Locks, of which the following is a specification.

This invention relates to door locks, and my object is to produce a simple lock construction which it will be difficult to pick, and also one in which the locking mechanism will act with accuracy and certainty.

It is a further object to provide a tumbler arrangement not likely to get out of order or be accidentally operated to lock the latch bar in case of slamming of the door.

With these objects in view, my invention comprises certain novel and peculiar features of construction as hereinafter described and particularly pointed out in the appended claims; and to afford a clear and complete understanding of the same, reference will be had to the accompanying drawing, forming a part of this specification, and in which—

Figure 1 is a side view of my improved lock with the face plate removed to disclose the interior, and also with a portion of the tumbler latch broken away, the tumbler mechanism being shown in unlocked position; Fig. 2 is a vertical section through the lock, being taken along the line II—II of Fig. 1, but with the face plate shown in place; Fig. 3 is a view similar to Fig. 1, but with the upper portion broken away and the tumbler mechanism shown in locking position; Fig. 4 is a perspective view of the latch bar and the tumbler latch carried thereby; and Fig. 5 is a plan view of the tumbler bar.

Referring to the drawing, the casing 2 of the lock accommodates the usual latch bar 4, provided with the latch piece 5 and with the tail pieces 6 for engagement by the operating lugs 8 secured to the knob shaft 10. The latch bar 4 is also provided with a lug 12 adapted to be engaged by a rocker arm 14 pivoted at 16 to the casing 2. This arm supports a weight 18, the tendency of which is to rock said arm in position to hold the latch bar normally advanced in order to project the latch piece 5.

At the rear of the latch piece 5 the bar 4 is offset, as shown at 20, the upper edge of

which offset portion is recessed to provide a notch 22 within which is slidably supported one end of the tumbler bar 24. The other end of the tumbler bar is slidably supported upon a hook 26 carried by the latch bar, the tumbler bar being held by the vertical arm of said hook against a lug or boss 28 formed upon the latch bar. For limiting the movement of the tumbler bar in one direction it is provided with a shoulder 30 adapted to abut against the offset portion 20, while movement of said bar in the opposite direction is stopped by a shoulder 32 formed on the casing 2, at which point the bar becomes locked against sliding movement on the hook, the latter entering a recess 34 in the under edge of the bar 24.

The locking engagement of the tumbler bar 24 with the hook 26 is insured by the dropping of the bar under the influence of not only its own weight, but also the action of an angularly formed tumbler latch 36 which bears upon the top edge of said bar and is pivoted at 38 to the latch bar. The pivoted end of the latch 36 extends through the recess 22 alongside the bar 24, and said latch is held under constant downward pressure by the weight 18, due to the left end of the arm 14 being bent into contact with the upper edge of said latch.

The part of the latch 36 which overlies the tumbler bar is provided with a detent 40 adapted to engage either side of a lug 42 formed on the upper edge of the tumbler bar, according as the latter is in locking or operative, or in unlocking or inoperative position.

The lower edges of the tumbler bar and latch 36 are suitably formed for engagement and operation by a key (not shown) properly constructed for the purpose. In Fig. 1, the parts are shown with the tumbler mechanism unlocked, and the latch bar free to be reciprocated by means of the knob shaft 10. In this position the tumbler bar is advanced with its shoulder 30 against the offset portion 20 of the latch bar and so held by the detent 40 dropping in to the left of the lug 42. In order to lock the tumbler mechanism, the key is inserted and the key-bit lifts the tumbler latch 36 without affecting the tumbler bar until the bit has reached the shoulder at the left side of the notch 44 in the tumbler bar, by which time the detent is disengaged from the lug 42, and the key-

bit, by bearing against said shoulder of the notch 44, throws the bar 24 to the left against the shoulder 32, whereupon the bar drops with its notch 34 in engagement with the hook 26 and the detent 40 falls in to the right of the lug 42. In this position of the parts, the latch bar can no longer be moved to the left to unlock the door, and the hook 26-notch 34 engagement and the locking of the lug 42 with the detent 40 afford a double security against any possible chance of the unlocking of the tumbler mechanism without the use of the proper key.

In the unlocking of the tumbler mechanism, the key being turned in the opposite direction, the key-bit first engages and lifts the latch 36 to release the detent from lug 42, and at the same time raises the bar 24 sufficiently to remove it from engagement with the hook 26, by which time the bit has reached the shoulder at the right of the notch 44, and further turning of the key throws the bar back to original position. It will thus be seen that picking of the lock would be extremely difficult in view of the fact that the tumbler bar must be released not only from the hook but also from the tumbler latch, and to accomplish this two independent movements are necessary because of the relative movement required between the tumbler bar and its latch in order to free the bar from the detent, and which could not well be effected by the means ordinarily employed in lock-tampering.

When the parts are in the position illustrated in Fig. 1, it will also be observed that the tumbler latch 36 affords an effective means for preventing any accidental locking of the tumbler mechanism in case the door should be suddenly slammed shut.

For closing the parts within the casing 2, I provide the usual face-plate 46, as shown in Fig. 2.

From the foregoing it will be apparent that I have provided a very simple and inexpensive device for carrying out the objects of my invention, and while I have illustrated and described what now appears to me to be the preferred form of the same, I wish to be understood as reserving the right to all changes and modifications which may fairly fall within the spirit and scope of the appended claims.

I claim—

1. In a door lock, a casing, a latch bar within the casing, a tumbler bar carried by said latch bar and adapted when in operative position to engage a fixed point on the casing for locking the latch bar, said bars being constructed and arranged to lock together when said tumbler bar is in operative position, and a tumbler latch pivoted to the latch bar for locking said tumbler bar in said position.

2. In a door lock, a casing, a latch bar

within said casing, a tumbler bar carried by said latch bar and adapted when in operative position to engage a fixed point on said casing for locking the latch bar, said bars being constructed and arranged to lock together when said tumbler bar is in operative position, and a tumbler latch pivoted to the latch bar for locking said tumbler bar in said position, said tumbler latch being also adapted to lock said tumbler bar in inoperative position.

3. In a door lock, the combination of a latch bar, a tumbler bar carried by said latch bar and movable into inoperative position or into operative position to lock said latch bar, pivoted means carried by said latch bar for locking the tumbler bar in either of said positions, and a vertically movable weight for preventing accidental upward or unlocking movement of said pivoted means.

4. In a door lock, the combination of a latch bar, a tumbler bar carried by said latch bar and movable into inoperative position or into operative position to lock said latch bar, and a pivoted latch carried by said latch bar and provided with a detent for engaging and locking said tumbler bar in either of said positions.

5. In a door lock, the combination of a latch bar, a tumbler bar movable into inoperative position or into operative position to lock said latch bar, means carried by said latch bar for locking the tumbler bar in either of said positions, and a yieldingly depressed arm pivoted to the casing of the lock and resting on said means to prevent accidental upward movement thereof.

6. In a door lock, the combination of a latch bar, a tumbler bar movable into inoperative position or into operative position to lock said latch bar, means whereby said bars interlock when said latch bar is locked, and pivoted means acting automatically to lock said tumbler bar in inoperative position and to supplementally lock it in operative position.

7. In a door lock, a casing, a latch bar within the casing, a tumbler bar slidably carried by said latch bar and adapted when in operative position to abut against a fixed point on the casing for locking said latch bar, means whereby said bars are interlocked when said latch bar is locked, and a tumbler latch pivoted to the latch bar and movable independently of said tumbler bar and adapted to latch said tumbler bar automatically in either operative or inoperative position.

8. In a door lock, a casing, a latch bar within the casing, a key-operated tumbler bar slidably carried by said latch bar and adapted when in operative position to abut against a fixed point on the casing for locking said latch bar, means whereby said bars

are interlocked when said latch bar is locked, and a key-operated tumbler latch adapted to latch pivoted to the latch bar and said tumbler bar in operative position, the unlatching of the tumbler bar taking place by a relative movement between it and said latch independently of the movement whereby said tumbler bar is unlocked from the latch bar.

19 9. In a door lock, the combination of a latch bar, a tumbler bar movable into inoperative position or into operative position to

lock said latch bar, a pivoted latch carried by said latch bar and adapted to engage and lock said tumbler bar in either of said positions, and a common means for yieldingly actuating said latch and said latch bar.

In testimony whereof, I affix my signature, in the presence of two witnesses.

LOUIS F. BONALY.
